(57) **CLAIM**

The ornamental design for a zipper, as shown and described.

DESCRIPTION

The SOLE FIGURE is a front view of a zipper showing my new design.

Any views of the zipper not shown in the figures (including the top, bottom, back, left side, and right side views) form no part of the claimed design.

The broken lines in the figures represent portions of the zipper that form no part of the claimed design.

1 Claim, 1 Drawing Sheet
